Primary Examiner — Katie Jane Stofko(74) *Attorney, Agent, or Firm* — Parsons Behle & Latimer(57) **CLAIM**

The ornamental design for a conical potato piece, as shown and described.

DESCRIPTION

FIG. 1 is a perspective view showing a conical potato piece embodying my new design;

FIG. 2 is a front plan view thereof;

FIG. 3 is a rear plan view thereof;

FIG. 4 is a left side plan view thereof;

FIG. 5 is a right side plan view thereof;

FIG. 6 is a top plan view thereof; and,

FIG. 7 is a bottom plan view thereof.

The evenly-spaced broken lines in FIGS. 1-7 illustrate portions of the conical potato piece that form no part of the claimed design. The dash-dot-dash broken lines in FIGS. 1, 4, and 5 illustrate the boundary of the claimed design which forms no part thereof.
